OSCILLATING STAIRS

Alexander Michael Georgiev and Leonard J.
Rawson, Dayton, Ohio

Application July 12, 1950, Serial No. 173,331

7 Claims. (Cl. 198—16)

1

This invention pertains to lifting equipment for transporting a load from one level to another by a plurality of increments totaling the distance between levels. When the load is a human being, he may be transported from one level to another by a succession of easy stages with minimum effort. The mechanized stairway will be useful in every home having two or more floors and will be a convenient piece of equipment for every person. A particular adapted for the home installation is its usage outdoors, such as for lifting a person or load from the street level to the house level. The conventional elevators, escalators and sliding chairs are not usable in such applications. While not designed with that in mind the equipment is particularly adapted to persons suffering from fatigue or illness whereby they may ascend or descend from one level to another with no more effort than walking on a level floor. While the mechanized stair can also be used for descent its primary purpose is to ease and facilitate a person or load in making ascent. When the load is an inanimate object such as a crate, lug-box or barrel, it may be started at the lowest level whereupon it will be transported from one level to another by a succession of lifts and self-shifting movements.

This is accomplished by alterations of a conventional stairway to incorporate a set of movable steps, or part of each step may be movable, to be driven by a power source for transporting the load from one level to another. The movable steps may be individually actuated, or they may be actuated in gangs or groups. Suitable control elements actuated from a point or points convenient to the stairway make it possible to start, stop and regulate the stair movement.

The broad definition for the invention is: a mechanized equipment that moves a load from one level to another stepwise, that is to say, lifts a load through a series of upward movements or upward and forward movements, effected by an external power means, as that of an electric motor, an hydraulic or pneumatic drive or the like. The amplitude of oscillation (in the case of motion at an incline) to be the distance between two similar points of two adjacent steps, multiplied by an integer. The individual steps may be raised and lowered one by one in proper sequence, i. e., first the lowest step, then the one above it and so on.

The raising and lowering of the individual steps can be effected by mechanical means driven by a suitable source of power, using pistons and cylinders, eccentrics or the like; or the movement

2

may be effected by electric means using solenoids or motors; or the movement may be effected by means of fluid pressure (hydraulic or pneumatic) and a collapsible chamber, such as a piston and cylinder bellows, Sylphon or other closed compartment. While the drawings and description particularly show and describe a liquid medium as the motivating means for the fluid pressure system, which necessitates a return circuit, the use of compressed air in place of liquid simplifies the conduit arrangement, since no provisions have to be made for return of the fluid. After it has performed the selected function it may be exhausted to the atmosphere. Application of the driving power for the individually actuated steps may be by personal selection for each step, such as by actuating a switch or valve when stepping upon one of the step treads, which gives a selected speed of progress, or the driving power may be applied automatically by one step actuating a valve or switch as it nears the end of its movement. On the other hand, the application of driving power may be controlled through the operation of a cycling unit that progressively applies the step actuating force to the first step and then to the next until the whole set of steps have been moved.

The raising and lowering of the gang of steps as a unit can be effected by any of the above mentioned means and appropriate linkage for powering the individually actuated steps. The control in any case may take the form of a valve or switch located at the head and foot of the stairway somewhat as a three-way switch remotely controlling an electric light, or by a single control valve or switch operable from either the head or foot of the stairs or at any point along the run of the stair structure. The control valve or switch may be fitted with a member actuatable from any point along the stairway, for instance a lever and cable or other linkage.

The preferred form of equipment is existent in the reciprocating gang stairway and is specifically illustrated and described herein, and necessitates only one moving unit with a single control. A valuable advantage of the equipment is the safety feature. No part of the equipment is lifted higher than the height of a conventional step or from one step level to another, and consequently no part of the equipment can drop more than the height of a step of the system. Contrasted with elevators and the like where a fall may, and has been experienced of one or more floors, the moving stairway is far less hazardous. There are a minimum of moving parts in the equip-

ment and the motions are simple, causing little wear. Contrasted with the escalator, its nearest relative, the reciprocating stairway is less expensive to install and maintain. The escalator is complicated to build and install, and there are a multiplicity of moving parts experiencing considerable wear and frequent replacement. Also the escalator needs additional space for the returning portions of the step conveying conveyor.

The reciprocating stairway has the unique feature of permitting an individual to stop his ascent or descent at any point of the transfer and return to the starting point without experiencing any inconvenience. Contrasted with this, a person using an elevator must usually continue to the next floor before he can return. In the case of an escalator the person using it can stop and return to the starting point only after reaching the other floor, or by walking down the upward moving stairway. Also, a person using the reciprocating stairway may pause at any point or step level, and not return to the starting point, but resume the trip to the object level at his will. That usually cannot be done with the moving elevator or escalator.

The reciprocating stairway, wherein the step movement is confined to the vertical, is adapted to superimpose or overlay relation to one side of the original and existing installation, and when operated moves the load vertically from one level to the next requiring movement of the load forward enough and sideways to place it on the tread of the next step. The vertical movable type of reciprocating stairway may be adapted to an angling, winding or spiral stairway, since the guides provide the correct up and down movement. In stairways of complicated design, such as complicated bends, simplification may justify skipping or omitting one or more steps. However, the discontinuity of the movable portion is practicable. In such cases the ascending person will have to lift himself by his own power only a step or two. That amounts to only a slight inconvenience, which however, may generally simplify the construction of the equipment. Where the steps are individually reciprocated and each embodies control means for actuating the step, the equipment is suitable for transporting inanimate objects, especially if the load, that is the inanimate object, can coast upon the treads of the steps which have an incline of a few degrees downward in the direction of the horizontal travel. To spread the usage of that type of equipment the treads of the inclined steps may incorporate the rollers that support the load and permit it to coast onto the adjacent step when moved to the new level.

In some cases it is advantageous and less costly to move the reciprocating gang of steps along the slope of an incline instead of vertically. However the vertically moving gang is more adaptable to existing stairways and to angled or spiral stairways. When a faster and smoother climbing rate is desired, both portions of the steps, or two parallel portions of the stairway can be made to reciprocate at the same time but moving in opposite directions, i. e., while one is traveling upward the second is traveling downward, both reversing in movement at the same time. The double action is adaptable to both types of reciprocating stairways, whether it be the vertical or the inclined type.

A particularly suitable type of reciprocating gang steps adapted for portability is the mechanized ladder which has a movable gang of steps

slidably mounted beside the conventional set of steps. The driving unit for that structure may be an electric motor with gear reduction and linkage for reciprocating the movable section the distance between two similar points of adjacent steps along the fixed set of steps. An extension cord then provides for connecting the power unit with a convenient source of electricity. Where the mechanized ladder is mounted on a fire truck or a utility service truck, the reciprocating portion may be driven by fluid pressure developed from the truck power plant. This type of equipment is very desirable with fire apparatus where firemen with heavy clothing are often required to carry equipment up and down a long flight of steps. Frequently, firemen are called upon to rescue persons from upper floors of a building. The descent is made less hazardous, and with less fatigue with the mechanized ladder.

Other objects and advantages will be in part evident and in part pointed out in the following description taken in connection with the accompanying illustrative drawings.

In the drawings wherein like numerals refer to like parts through the several views,

Fig. 1 is a fragmentary view in perspective showing schematically one form of our improved stairway for conveying a person from one floor level to another, by means of one movable flight and one fixed flight of steps.

Fig. 2 is a similar view of another form of our improved stairway wherein two movable flights are operated for transporting a person at a faster rate.

Fig. 3 is a view similar to Fig. 2, but showing the double flight of movable steps in a reversed position, or at the other end of the range of reciprocation.

Fig. 4 is a schematic view in side elevation of our improved stairway where the entire gang of steps is reciprocated vertically by one type of power device.

Fig. 5 is an elevational view showing schematically how the invention is applied to a motorized ladder.

Fig. 6 is an installation view in perspective showing our favored type of construction where the movable gang of steps is movable along an incline, one wall of the supporting structure having been removed for purposes of illustration.

Fig. 7 is a transverse sectional view substantially as indicated by the line and arrows 7-7 of Fig. 6.

Fig. 8 is a longitudinal sectional view through the improved stairway substantially as indicated by the line and arrows 8-8 of Fig. 6, the view being taken through the movable section of stairs or steps and showing the power means for operating the movable steps.

Fig. 9 is an underneath view of the stairway shown in Fig. 8, substantially as indicated by the arrow 8.

Fig. 10 is a sectional view of a modified safety feature.

Fig. 11 is a fragmentary view in section showing details of the control apparatus for starting and stopping the movable portion of the steps substantially as indicated by the lines and arrows 11-11 of Figs. 8 and 12.

Fig. 12 is an elevational view of the same substantially as indicated by the arrow 12 in Fig. 11.

Figs. 13 and 14 are details of the power control device.

Fig. 15 is a fragmentary view, showing in side

elevation, an alternative means for actuating the movable portion of our improved stairway.

Fig. 16 is a fragmentary view in elevation illustrating schematically one type of individually movable step.

Fig. 17 is a sectional view through the same substantially as indicated by the line and arrows 17-17 of Fig. 16.

Fig. 18 is a sectional view of a control valve for individually actuating single steps operated by fluid pressure.

Fig. 19 is a sectional view of individually operated steps for transporting inanimate loads.

With reference to the drawings, and first with respect to the reciprocating gang of steps, as shown in Figs. 1 to 3 inclusive, 30 indicates a string of fixed steps 1, 3, 5 and 7 connected by the usual risers and all supported by stringers 32 one of which is shown in Fig. 1. A reciprocatable string of steps 34 has steps 2, 4, 6 and 8 connected by the usual risers and supported by stringers 36. In Fig. 1 the movable string of steps 34 is actuated by a power device 38 having cranks 40 and pitmans 42, which when actuated cause the movable string of steps 34 to reciprocate between limits along the extent of the fixed string 30. The range of movement is the slant length of distance between similar points on two adjacent steps. In Fig. 1 the movable string 34 is in the lower position where step 4 is lined up level with step 1, and when moved to the other limit the step 4 is lined up with fixed step 3.

In Figs. 2 and 3 there are two movable strings of steps which are marked 34L for the left hand section and 34R for the right hand section. The steps are similarly connected by the conventional risers and supported by like stringers which are pivotally connected by pitmans 42L and 42R actuated by cranks 40L and 40R driven by the power device 38. The cranks 40L and 40R in Figs. 2 and 3 are disposed 180 degrees apart so that as they are driven by the power device 38, the two sections are moved in opposite directions. In Fig. 2 the string of steps 34L is at the lower limit while the string 34R at its upper limit, so that steps 2, 4 and 6 are level with steps 3, 5 and 7 respectively. In Fig. 3 the string 34L is at the upper limit with the string 34R at the down limit. The steps 4, 6 and 8 are there level with steps 1, 3 and 5. A specific construction of the movably inclined single gang is shown in Figs. 6 to 14 inclusive, described with respect to an actual installation.

The fixed string of steps 30 is secured to a wall 44 and extends between floors 1 and 28 by means of stringers appropriately notched to unite with the step risers 46 and treads 48 as shown in Figs. 6 and 8. This string of steps made up of the treads 48 and the risers 46 make up the odd numbered steps 3, 5, 7, 9, 11, 13, 15, 17, 19, 21, 23 and 25, the last being level or flush with the upper floor level 28. It is adaptable to the conventional means of traveling between floors. A movable string of steps 34 also movably extends between the floors 1 and 28, being made up of treads and risers as in the fixed string 30 to provide the even numbered steps 2, 4, 6, 8, 10, 12, 14, 16, 18, 20, 22 and 24. These steps are mounted on stringers 36 in like manner to the fixed string 30, and the stringers 36 are fitted with channels 50 opening outwardly to receive rollers 52 secured to rigid structure of the building such as the wall member 54 and the adjacent stringer 32 of the fixed string of steps. The channels and rollers provide guideways for the movable string of

steps 34 so that it may be reciprocated along the slant length of the stairway parallel with the fixed string 30.

Movement or reciprocation of the string of steps 34 is accomplished by the pitmans or links 42 attached to the stringers 36 at 37 and connecting with the cranks 40 of the power device 38 as shown in Figs. 8 and 9. The power device illustrated comprises a gear reduction between a pulley 56 and the crank-shaft 58. An electric motor 60 mounted on a base 62 is belted or otherwise geared to the pulley 56 by a belt or chain 54. The gear reduction and the motor are mounted on a frame-work 66 suitably disposed beneath the stairs for coupling of the cranks and pitmans with the stringers of the movable portion of the stairs. The framework with its gear reduction and motor may be assembled as a complete unit so that it may be moved into place beneath the stairway and secured to the floor of a closet, or it may be slung or supported in an inclined position as shown in Fig. 8 in which position it will give ample head room for a second flight beneath and leading to a lower floor.

Safety means are incorporated at each end of the movable set of steps so that a person will not stumble over an unexpected portion or get his foot caught in any opening while the stairs are moving. The top step, 26 of the movable section as shown in Figs. 6 and 8, is mounted on a pair of rails 68 each carrying channel member 70 engaging rollers 72 mounted on horizontal floor joists 73 supporting the floor 28. Thus the step 26 is capable of sliding horizontally beneath the floor 28 as the step 24 is raised to the level of step 25. Means are provided, including a spring, weight or linkage, effecting the return slide of the step 26 forward as the movable string moves downward. With respect to the lowest movable step 2, the stringers 36 are extended downwardly to be covered by an apron 74 which slants to the same degree and direction as the inclination of the string of steps. When the steps are moved to the upper position, the apron will cover any opening left in the floor 1 by the moving step 2, somewhat as shown in the lower part of Fig. 10. As shown in Fig. 7, a filler piece 36a is secured to the side of the stringer 36 to fill in the thickness of the channel 50 and roller 52 between the two sections of steps. That prevents a person getting his foot caught between the proximate ends of the fixed steps and the movable steps when the stairway is operating.

The rest position of the movable string of steps in Figs. 6 and 8 is in the down position where the movable step 2 is flush with the lower floor 1, and where the safety step 26 is projected forward to align with the fixed step 25 and the upper floor level 28. In Fig. 10, a modification of the safety measures is shown for each end of the movable string of steps. The apron 74 at the lower end of the movable steps is here joined to the front edge of movable step 4 instead of to the front edge of step 2 as in Fig. 6. At the upper end of the movable string step 26 telescopes over an apron 76 supported by the floor joists 73 so that it slants downward from the front edge of the floor 28. When the movable string of steps in Fig. 10 slides from the upward or rest position as shown to the lower position, the apron 74 at the lower end of the steps will disappear while the upper apron 76 will be exposed by the downward movement of step 26. Thus, in neither instance can a person place his foot in such a position that it will be caught between relatively movable parts

of the equipment. All potential openings while the movable stairway is at rest are covered, and are kept covered while moving until a position is reached by the movable steps that is proper for stepping on for travel.

Control of the power device for starting and stopping the movement of the reciprocating gang of steps is accomplished by the switch 77 and controller 79 shown in Figs. 11 to 14 where a mercury bulb circuit closer 80 is mounted in a pivoting bracket 82 oscillatable about a pin 84 carried by a slide bar 86, so as to be moved into an obstructing and into a free position with respect to some movable part of the sliding stairway. A spring 88 wound around the pivot pin 84, engages the bracket 82 and an anchor post 90 to urge the switch and bracket to the horizontal position engaging a stop pin 91 as shown in Fig. 13, where a roller 92 carried by the bracket 82 is disposed in the path of the moving part of the stairway. The bar 86 has a pair of slots 94 arranged along the length thereof through which screws or the like 96 extend loosely to thread into a fixed part 97 mounted on the underside of fixed stringers 32 so that the bar may slide toward and away from the movable string of steps as limited by the slots and screws. Fixed to one of the screws 96 there is a clip 99 providing an anchorage for a coil spring 98 that is attached at the other end to the bar 86 which spring normally moves the bar 86 toward the moving part of the stairway as shown in Fig. 11.

A cord or cable 100 attached to the bar 86 trains over a pulley 102 within the wall 44 and then trains over a second pulley 104 to return through the wall 44 and attach to an oscillatable lever 106 which is operable by hand to control movement of the stairway. The lever 106 is pivoted in the bracket 108 of the hand rail 110, and is coupled with a control bar 112 extending the length of the handrail so that the control lever may be actuated at any point along the extent of the stairway. Other brackets 108 support the control bar and hand rail along the slant length of the stairway as shown in Figs. 6 and 8, where along with Fig. 11 it is apparent that pulling the control bar 112 away from the wall 44 and downward toward the hand rail 110, moves the control switch 77 disengaging any part of the movable string of steps. That permits the switch bulb 80 to oscillate to a horizontal position so that its contact points 114 and 116 will be bridged by the mercury mass 118. The contact points 114 and 116 are joined to conductors 120 and 122 respectively, 120 communicating with one side of the motor 60 and 122 leading to a current source not shown. A conductor 124 connects the other side of the motor with the current source. Thus, the switch 77 controls the flow of current to the motor 60 for operating the movable section of the stairs. When the mercury mass 118 bridges the contact points 114 and 116 the motor 60 is energized and drives the power device 38 so that the movable gang of steps 34 slides up and down as guided by the channels 50 and rollers 52.

To stop movement of the steps, the control bar 112 is pushed toward the wall 44 at any point along its length which permits the switch 77 to be moved into the path of the movable section of stairs. It is desirable that the moving section of steps always stop in the same position, and in such a position that no hazardous traps be left to endanger a person when approaching the stairway. The control switch 77 is therefore mounted

in a position and attitude suitable to be tilted to the circuit open condition when the moving stairway has reached the preferred rest position, such as at the end of the downward travel shown in Figs. 6 and 8, such as at the end of the upward travel in Fig. 10. As shown in Figs. 11 to 14 inclusive, the switch 77 is mounted in a position and attitude to be tilted to circuit open condition by some part of an upwardly moving stair section such as shown in Fig. 10.

To be suitable for tilting to circuit open condition by some part of a downwardly moving stair section, suitable for control of the structure shown in Figs. 6 and 8, it is to be understood that the switch structure 77 of Figs. 13 and 14 would be mounted in inverted position, so that when engaged by the moving stair section it would be tilted downwardly to the circuit open position. That might be done without change of structure by removing and turning over the switch bracket 82. The switch and bracket are then assembled on the support in inverted relation from that shown in Fig. 14 so that it may pivot on pin 90 and have the spring 88 engage the pin 84 to urge the bracket upwardly against the stop pin 91a. In that attitude, the horizontal position of the bulb 80 closes the motor circuit and the downward tilted position opens the motor circuit, which is effected by the downward moving section of the steps. In some types of mercury bulb switches it may be necessary to reverse the bulb with respect to the bracket so that the proper circuit relation can be obtained. In either instance, if the switch 77 is moved against the movable section while it is moving away from the rest position, the bulb 80 will not be tilted because the relative movement of the stair section is such as to bias the bracket 82 against the stop pin 91 or 91a, as the case may be. The moving part of the stairs soon disengages the roller 92 and leaves the bracket 82 in the horizontal position and under the urge of the springs 88 and 98 somewhat as shown in Fig. 13.

Reverse movement of the stairway, that is movement toward the rest position will engage the bracket and eventually tilt the bulb 80 to the circuit open position at the proper instant to stop movement of the stair section in the desired rest position. Fig. 14 shows the switch in open circuit position when installed for control of a moving stairway having a rest position at the upper end of the stroke, in the nature of that shown in Fig. 10. Actuation of the control bar 112 for starting the movement of the stairs of either type, acts to pull the bar 86 and the switch that it supports away from the stair stringer, to the extent limited by the slots 94 which allows the bracket 82 to pivot to the horizontal position under the influence of the spring 88 despite the rest position of the movable section of steps. In the horizontal position of the bracket the switch 77 completes an electrical circuit through the motor 60 over the power leads 120, 122 and 124, and the power device drives the movable part of the stairway. Obviously, the switch structure 77 and its actuating means may be adapted for the control of any type of moving stairway, it being only necessary to movably mount it so that it is out of the path of some moving part of the structure while the stair or step movement is desired, and so that it is in the path of some moving part of the structure when it is desired to stop the stair or step movement. Other means than the described switch may be used for lining up the steps in the rest position, and may include photo-elec-

tric cells and relays, with perhaps the inclusion of motor brakes. On the other hand, the electric motor 60 may incorporate or be fitted with an electromagnetic brake to facilitate stopping the stairs when the two sections are in the desired alignment.

In Fig. 15 the movable flight 34 is actuated by a power device 38 of modified form. It may embody a piston and cylinder 126 mounted on a fixed support 128 and have its piston rod 130 attached to a bracket 132 carried by one of the stringers 36. Conduits 134 and 136 connect with opposite sides of the piston and lead to a pump and cycling unit 138 driven by a motor or the like 60 under control of the switch 17. When the pump and cycling unit 138 are operating the stair section 34 is caused to slide up and down along the incline the extent of travel between two adjacent step levels such that the bracket 132 moves from the solid line position to the dotted line position indicated at 132a. In that raised position the step 12 will be on a level with step 13 as shown by dotted lines. The other steps of the movable section will be raised an equal amount. As the fluid medium is delivered by the pump and cycling unit through the conduit 134 to project the piston, the conduit 136 returns the fluid medium in front of the piston to the pump and cycling unit, or to a reservoir connected with it.

As the piston reaches the limit of its projected stroke, the cycling unit driven by the motor reverses the flow through the conduits 134 and 136 to retract the piston to the full line position. When the piston reaches the end of the inward stroke the cycling unit with its pump again reverses the flow and again projects the piston outward, which reversals continue so long as the switch 17 is closed. When the switch is moved into the path of some moving part of the stairway it is tilted to a circuit open condition which stops the movable stairway in the rest position. On the other hand, the power device 38 might well be an electrical device, or a mechanical unit driven by an electrical device, and might include an actuator of the ball screw and nut type used in aircraft for raising and lowering landing gear and moving control surfaces, being driven by reversible electric motors with limit switches determining the extent and direction of travel.

The reciprocating gang type of steps is further illustrated in Fig. 5 as having its embodiment in a ladder of portable construction to be carried around, or mounted on a truck for transportation. The fixed string of steps 30 comprises rails 138 and 140 spanned by rungs 142 providing the relatively fixed steps 1, 3, 5, 7, 9, 11, 13, 15, 17 and 19. A third rail 144 in parallel spaced relation to the ladder rail 140 forms a guide way for the sliding section of steps 34 which consists of rails 146 and 148 connected by rungs 150 forming the steps 2, 4, 6, 8, 10, 12, 14, 16, 18 and 20. The ladder rails 138, 140 and 144 are secured to a base member 152 which carries a suitable power device 38 providing a crank 40 and pitman 42 drivingly connected to the rung forming the step 2, of the movable string of steps. When the power device is operated the movable section 34 is caused to slide up and down along the guides 140 and 144.

One structural form of the vertically movable gang type of steps that is suitable for superimposing over one end of an existing stairway, is shown in Fig. 4. The movable gang 34 is suitably disposed within appropriate guides for vertical movement, and has brackets 156 to which

are coupled piston rods 158 of a piston and cylinder 160 providing the power device 38. There are two power devices 38 situated along the length of the stringers 36 though more may be used if necessary, and all are connected by the conduits 134 and 136 to a pump and cycling unit 138 similar to Fig. 15. Both power devices 38 are mounted on a rigid supporting structure 162 beneath the stairway, and all of the conduits 134 are joined to a common pipe or passage leading to one side of the cycling switch while the other side of the cycling switch similarly connects to the conduits 136 of all the power devices so that the piston and cylinder devices will be actuated equally and in the same direction at the same time.

When the stairway is in motion the even numbered steps are raised and lowered the distance between levels of adjacent steps as indicated at A. Steps 2, 4, 6, 8, 10, 12, 14 and 16 move from the solid line position shown in Fig. 4 to the level of the fixed steps indicated by dashed lines at 3, 5, 7, 9, 11, 13, 15 and 17 respectively. Obviously, the electrical means for driving the movable structure of Fig. 15 may also be used for driving the vertical gang of steps, and when controlled by the switch 17, makes for starting and stopping of the stairs at any point.

In Figs. 16, 17 and 18 there is shown mechanism for individually actuating steps in a progressive fashion. Mounted on the horizontal faces 164 of the stringers 36 there are guide posts 166 capped by head members 168 to which bellows walls 170 are attached for connecting the tread 172 and making a collapsible and expansible chamber 174 whose sides are reinforced by a box-like structure including the members 176 and 178 that are capable of telescoping over the head member 168. Traversing the guide-posts 166 there are rigid tubes 180 and 182 secured at the upper end to a valve box 184 secured to the underside of the tread member 172, thereby extending vertically through the bellows chamber 174 and slidably through the head members 168. At the lower end of the pipes 180 and 182 there are flexible pipe or hose connections 186 and 188 that join fluid pressure lines 190, 192 leading to and from a fluid pump 194 driven by a motor 60. An expansion chamber or fluid accumulator 196 may be incorporated in the pump output line to smooth out the operation of the mechanism.

The line 190 is a suction line and connects with the pipe 180 of all step lifting motors, for connecting with the intake to the pump 194, while the line 192 is a pressure line and connects with the pipes 182 of all step lifting motors for connecting with the output side of the pump. When the driving motor 60 is energized the pump 194 tends to draw the fluid medium out of the pipe 190 and its connecting cavities and force the medium into the pipe 192 and its cavities. The rise and lowering of the steps is controlled by the valve box 184 shown in enlarged detail in Fig. 18. Within the valve box 184 which is open to the chamber 174 there is a valve body 197 fixed to the underside of the tread member 172 and provides open ports 198 and 200 connecting the bore of the body 196 with the chamber 174. A pair of control ports 202 and 204 connect the bore of the body with passages 206 and 208 that in turn connect with the pipes 180 and 182 respectively. A spool valve 210 is movable along the bore of the body by a stem 212 extending upward through the tread 172 to engage a false tread 214 hinged to the front edge of the real tread. The valve

11

210 is thrust upward by a spring 216 so that a valving land 218 normally closes off the control port 204 to the pressure line 182. An enlargement 219 of the stem 212 acts as a stop for the valve 210 so that in the spring pressed or normal position the control port 202 is open to the suction line 180.

The drain ports 198 and 200 are open to the bore of the body and to the interior of the valve box 184 which is open through the holes 220 to the bellows chamber 174. The control valve is actuated by stepping upon the false tread 214 which depresses the valve 210 to close the suction port 202 and open the pressure port 204 to the open port 198. In this depressed position of the valve, the flow of fluid medium from the pump 194 fills the chamber 174 and expands the bellows 170 which raises the step to the upper limit. In Fig. 17, steps number 20 and 24 are shown in the rest or down position ready to be raised by the pressure from the pump 194, and the step number 22 is shown in the projected or raised position level with the step 24. When the foot is removed from the false step, the valve returns to the up position closing the pressure port 204 and opening the suction port 202 to the port 200 so that the chamber 174 is now connected to the intake of the pump 194, which withdraws the fluid medium from the chamber 174 for collapsing the bellows and lowering the step to the rest position. Thus, a person may be transported from a lower level to a higher level by successively stepping on the tread of the next step, after being raised to that level by the flow of fluid pressure into the corresponding chamber incident to opening of the pressure port by shifting the load onto the lowered step.

The progressively actuated steps with an adaptation to the transporting of inanimate objects, such as a lug box, crate or parcel, is illustrated in Fig. 19 where the step stringers 36 similarly support a number of steps for vertical guided movement by means similar to that shown in Figs. 16 to 18. The tread of each step in Fig. 19 is not horizontal but slants downward therefrom with respect to the tread nosing, and mounted in the tread of each step there are a plurality of rollers 222 arranged parallel with the tread nosing. A tread lever 224 is placed near the back edge of step, and normally projects above the rollers 222, but when depressed will actuate the valve 210 to admit fluid pressure to the corresponding bellows chamber 174. When this type of moving stairway is in operation, step number 2 will be in the rest position shown in dotted lines where it is level with the floor 1.

The article 226 to be transported to the level 28 is placed on the roller tread of step number 2 which depresses the valve 210 as explained with respect to Figs. 16 to 18. Fluid pressure raises the step number 2 with its load to the level of step number 4 as shown in Fig. 19, the load 226 then being free to coast down the incline of the slanting treads from step 2 onto the tread of step 4. In doing so, the tread lever 224 of step 2 is released and the tread lever of step 4 is depressed. The chamber 174 of step 2 being connected to pump intake is now collapsed with accompanying descent of the step, while the chamber 174 of step 4 is expanded, since it is connected to the pump output line. The step 4 with its load 226 is thereby raised to the level of step 6 and so on until the load reaches the level of floor 28 where it is taken away by an attendant or a conveyor. At each step level the load coasts

75

12

on the rollers 222 toward the back of the step tread until it bumps against the riser of the next step. As the step carrying the load rises clear of the riser on the adjacent step the load coasts down the incline of the tread onto the tread of the next step, and in doing so releases the control valve for one step and actuates the control valve for the next step, thus providing a progressive movement, step by step, from one level to another.

While we have, for the sake of clearness and in order to disclose our invention so that the same can be readily understood, described and illustrated specific devices and arrangements, we desire to have it understood that this invention is not limited to the specific means disclosed but may be embodied in other ways that will suggest themselves, in view of this broad disclosure, to persons skilled in the art.

Having thus described the invention, what we claim and desire to secure by Letters Patent is:

1. Transporting equipment for moving a person from one floor level to another floor level, comprising in combination, a reciprocating mechanism extending between floor levels, a fixed mechanism extending between the floor levels parallel with the reciprocating mechanism, both of said mechanisms having equally spaced foot rests extending throughout the length of the mechanisms, power means for actuating the reciprocating mechanism so that its foot rests move from one foot rest level to another of the fixed mechanisms, and then move back to the level of the first foot rest, and control means for the power means whereby a person may start and stop the reciprocating mechanism at any point along the extent of the mechanisms.

2. In transporting equipment for moving persons from one level to another without the person exerting muscular effort other than to walk on the level, the combination comprising, a fixed string of steps extending from one level to an adjacent level, a second string of steps beside the fixed string of steps and normally having its steps on the same level with the steps of the fixed string but movable to the level of an adjacent step, means under control of the person to be transported for moving the second string of steps throughout the spacing of two adjacent steps of the fixed string, and means under control of the moving string of steps for stopping the movement of the said second string at the normal position wherein the steps of the movable string will come to rest level with the steps of the fixed string.

3. A stairway for transporting a person from one floor level to another comprising in combination, a string of steps mounted on stringers and providing a plurality of steps of uniform tread and riser aggregating the distance between levels, spaced foot rests fixed along the extent of steps, guide rails secured to the stringers, rollers co-operating with each guide rail and permitting the string of steps to slide on an incline toward and away from each floor level, actuating means coupled to the stringers of the steps for reciprocating the steps between the levels of two adjacent treads, power means for driving the actuating means, and a manually actuated means extending along the string of steps for controlling the operation of the power means.

4. A stairway for transporting a person from one floor level to another comprising in combination, a string of steps mounted on stringers and providing a plurality of steps of uniform tread

and riser aggregating the distance between levels, spaced foot rests fixed along the extent of steps, guide rails secured to the stringers, rollers co-operating with each guide rail for confining the string of steps to slide on an incline toward and away from each floor level, actuating means coupled to the stringers of the steps for reciprocating the steps between the levels of two adjacent treads, power means for driving the actuating means, and a manually actuated means for controlling the operation of the power means and power interrupting means in parallel with the manually actuated means and actuatable at any point along the step reciprocation for stopping the steps on a level with the foot rests when the manually actuated means has cut off operation of the power means.

5. The combination set forth in claim 3, wherein in the manually actuated means includes a manually operable member adapted to be moved by a person at any position along the extent of the string of steps, a movable switch support adapted to be moved by said manually operable member, and a power switch carried by the movable support and which when in one position of the movable support is operated by the moving string of steps to interrupt the power means only when the steps are level with the foot rests.

6. In an oscillating stairs for transporting persons between floor levels, the combination comprising, a set of immovable steps extending between said floor levels, a set of movable steps rigidly connected together and slidably mounted for movement as a unit along the extent of the set of immovable steps, power means for reciprocating the movable set of steps between limits

5 coincident with the level of successive steps of the immovable set of steps, and manual control means for the power means including an electric switch having a circuit opening member movable into and out of the path of movement of the movable set of steps, and means locating the switch for engagement of the circuit opening member only at one end of the stair reciprocation whereby the movable steps will always come to rest at the level of the immovable steps.

10 7. In an oscillating stairs, the combination comprising, a movable set of steps having risers and treads for supporting a load thereon, power means for oscillating the steps along a path of movement having limits coincident with spaced tread levels, control means for starting and stopping the power means, and positioning means cooperable with the control means for stopping the set of steps at one of the said limits of oscillation whereby the steps will always be arrested with the treads flush with one of said spaced tread levels.
